DICYANDIAMIDE SULFONATES

Joseph H. Paden and Alexander F. MacLean,
Stamford, Conn., assignors to American Cyana-
m'd Company, New York, N. Y., a corporation
of Maine

No Drawing. Application October 25, 1945,
Serial No. 624,581

9 Claims. (Cl. 260—501)

1

This invention relates to the sulfonic acid salts of dicyandiamide and to methods of preparing the same.

It has been recorded in the literature that dicyandiamide, a neutral compound having a low ionization constant would not form salts with acids in aqueous solutions. In spite of this argument which refutes the formation of such salts, it has now been discovered that sulfonated salts of dicyandiamide can be prepared.

The sulfonate salts are prepared by reacting dicyandiamide with a sulfonic acid in a solvent for either or both of the reactants. Suitable solvents are ethers, esters, ketones, acids and the like. The following examples will serve to illustrate the preparation of sulfonate salts of dicyandiamide:

EXAMPLE 1

Dicyandiamide p-toluenesulfonate

Reagents	Molar Ratio
Dicyandiamide.....	1.00
p-Toluenesulfonic acid.....	1.23
Acetic acid, glacial.....	4.36

The dicyandiamide is added slowly to the mechanically stirred acetic acid solution of the p-toluenesulfonic acid at 25° C. The product begins to crystallize from solution before the addition of the dicyandiamide is completed. After completion of the addition of the dicyandiamide, the reaction mixture is then cooled to 20° C. The colorless crystals are filtered, washed with methyl ethyl ketone containing a small amount of p-toluene sulfonic acid and dried under vacuum at 50° C. By means of potentiometric titration, the molecular weight was found to agree closely with the theoretical value of 256.

Dicyandiamide p-toluenesulfonate does not have a sharp melting or decomposition point, and since analytical data checks the theoretical composition, the optical and crystallographic properties are herein presented to characterize the p-toluenesulfonate. Dicyandiamide p-toluenesulfonate is a white, columnar solid with curved faces and a negative optic sign. In white light the refractive indices are as follows: $\alpha=1.547$; $\beta=1.582$; and $\gamma=1.598$. The apparent optic axial angles as observed in air are estimated to be greater than 100°, and the true optic axial angle estimated therefrom is greater than 54°. The principal vibration direction of α is at an angle of $30^\circ \pm 1'$ to the elongation of the crystal.

2

EXAMPLE 2

Dicyandiamide benzylsulfonate

Reagents	Molar Ratio
Dicyandiamide.....	1.00
Benzylsulfonic acid.....	1.16
Acetic acid, glacial.....	4.00

10 Small portions of the benzylsulfonic acid are added to an agitated mixture of dicyandiamide and acetic acid at a temperature of substantially 40° C. The reaction mixture is stirred about one hour after the last portion of benzylsulfonic acid is added and the temperature is lowered to substantially 20° C. The solid dicyandiamide benzylsulfonate is filtered, washed with methyl ethyl ketone containing 5% benzylsulfonic acid and dried under vacuum at about 70° C.

20 Dicyandiamide benzylsulfonate melts at 138° C., then resolidifies. The optical and crystallographic properties are herein presented to characterize this salt. Dicyandiamide benzylsulfonate is a white, lamellar solid with broken edges and positive optic sign. In white light the refractive indices are as follows: $\alpha=1.485$; and $\beta=1.590$. The apparent optic axial angle as observed in air is estimated to be greater than 100° and the true optic axial angle estimated therefrom is greater than 60°. The optic axial plane or principal optic section is perpendicular to the crystal face presented.

EXAMPLE 3

Dicyandiamide ethylsulfonate

Reagents	Molar Ratio
Dicyandiamide.....	1.00
Ethylsulfonic acid.....	2.56
Acetic acid, glacial.....	31.80

35 A mixture of the above reagents is agitated at substantially 40° C. until a clear solution forms. After this solution is cooled to about 20° C. crystals are slowly deposited. Upon completion of the crystallization of dicyandiamide ethylsulfonate the latter is filtered, washed with methyl ethyl ketone and dried under vacuum at substantially 60° C.

45 Dicyandiamide ethylsulfonate is a white tabular solid which has the forms (100) (010) (001), has the cleavages along the planes (100) (001), and has a negative optic sign. In white light the refractive indices are as follows: $\alpha=1.497$; $\beta=1.551$; and $\gamma=1.569$. The apparent optic ax-

ial angle as observed in air is 90° and the true optic axial angle is 54° . The optic axial plane or principal optic section is perpendicular to the plane (010). The principal vibration directions are such that β is at an angle of $3^\circ \pm 30'$, to "c" and γ is parallel to "b." It is to be understood that "b" and "c" are the crystallographic axes.

The sulfonates described in the above examples are typical of those that may be prepared by the present invention.

The sulfonate salts of dicyandiamide are useful as chemical intermediates in the preparation of flameproofing compositions, chemotherapeutic agents, insecticides, synthetic resins and for other purposes.

While the invention has been described with particular reference to specific embodiments, it is to be understood that it is not to be limited thereto, but is to be construed broadly and restricted solely by the scope of the appended claims.

What is claimed:

1. Sulfonic acid salts of dicyandiamide.
2. Dicyandiamide p-toluenesulfonate.
3. Dicyandiamide benzylsulfonate.
4. Dicyandiamide ethylsulfonate.
5. A method of preparing sulfonate salts of dicyandiamide which includes the steps of reacting dicyandiamide with a sulfonic acid in a solvent for the dicyandiamide and sulfonic acid below substantially 50°C .
6. A method of preparing sulfonate salts of dicyandiamide which includes the steps of reacting in acetic acid dicyandiamide and a sulfonic acid below substantially 50°C , and recovering the dicyandiamide sulfonate therefrom.
7. A method of preparing dicyandiamide p-toluenesulfonate which includes the steps of reacting in acetic acid dicyandiamide with p-toluenesulfonic acid below substantially 50°C , and

recovering the dicyandiamide p-toluenesulfonate therefrom.

8. A method of preparing dicyandiamide benzylsulfonate which includes the steps of reacting in acetic acid dicyandiamide with benzylsulfonic acid below substantially 50°C , and recovering the dicyandiamide benzylsulfonate.

9. A method of preparing dicyandiamide ethylsulfonate which includes the steps of reacting in acetic acid dicyandiamide with ethylsulfonic acid below substantially 50°C , and recovering the dicyandiamide ethylsulfonate therefrom.

JOSEPH H. PADEN.
